(57) **CLAIM**

The ornamental design for a work light handle grip, as shown and described.

DESCRIPTION

FIG. 1 is a perspective view of a work light handle grip showing my new design;

FIG. 2 is a second perspective view thereof;

FIG. 3 is a front view thereof;

FIG. 4 is a left side view thereof, the right side view being a mirror image thereof;

FIG. 5 is a top view thereof; and,

FIG. 6 is a bottom view thereof.

The broken line showing represents unclaimed portions of a work light and forms no part of the claimed design.
